UNITED STATES PATENT OFFICE.

BASIL MAGOR, OF NEW YORK, N. Y., ASSIGNOR TO MAGOR CAR COMPANY, OF NEW YORK, N. Y., A CORPORATION OF NEW JERSEY.

LOGGING-CAR.

1,103,975.

Specification of Letters Patent. Patented July 21, 1914.

Application filed May 3, 1911, Serial No. 624,839. Renewed March 25, 1914. Serial No. 827,248.

To all whom it may concern:

Be it known that I, BASIL MAGOR, a subject of the King of Great Britain, and a resident of the borough of Manhattan of the city of New York, in the State of New York, have invented certain new and useful Improvements in Logging-Cars, of which the following is a specification, reference being had to the accompanying drawings, 10 forming a part hereof.

The object of the invention is to simplify and improve the construction of the log-supporting bunks and their associated parts, in logging cars or trucks.

15 Referring to the accompanying drawings: Figure 1 is a plan view of a portion of a truck in which the improvements are embodied, considerable of the detail being shown in dotted lines. Fig. 2 is a side view, 20 Fig. 3 an end view, partly broken out for purpose of clearer illustration; and Fig. 4 is a cross sectional view on the line 4—4 of Fig. 3, the stake-controlling chains being omitted for the sake of clearer illustration.

The truck is denoted generally by *a* and the log-supporting bunk, which extends transversely across the same, by *b*. The upper face of the bunk upon which the logs 30 rest will be seen to consist of a channel-plate *b*¹ preferably inverted and supported directly upon the top of the center sill or girder *c* which connects two trucks to form a car (the complementary truck being omitted from the drawing); and angles *b*² may be provided, as on each side of the center of the channel to secure it to the sill *c*. This construction furnishes a broad surface for the logs to rest upon, and covers up the stake 35 controlling chains *t*. The lower face of the bunk is also preferably a channel plate, and the two channel plates, thus constituting the top and bottom members or faces of the bunk, are united around the center sill by means of side pieces such as plates or braces, 40 as shown particularly in Fig. 3. These plates or braces may be conveniently secured to the flanges of the channels, and constitute the sides of the bunk. The angle plates *b*² 45 obviously serve to bind the bunk more firmly to the center sill and to prevent the same from twisting upon the center sill. It will thus be seen that the bunk is built around and secured to the center sill without the 50 necessity of cutting through or recessing

the center sill in order to permit a part of the bunk to lie in or extend through the same. This is of considerable advantage in view of the fact that it is often inconvenient or unwise to cut into the center sill or main girder or reach member any more than can be helped. The chains *t* are secured one to each stake *l*, consisting preferably of an arch-shaped strip of steel pivoted on its ends to the end of the bunk, and extend along 60 inside the bunk underneath the channel *b*¹ and between the latter and the center sill *c* to opposite sides of the bunk where they project through openings *b*³ in the sides of the bunk. Near this opening and upon the 65 same side of the bunk, fastening means *o*¹ are provided to secure the end of the chain and thus hold the stake at the opposite end of the bunk in its elevated or normal position for retaining the logs. It will be seen 70 that by inverting the channel-plate *b*¹ and resting its flanges down upon the girder *c*, a very convenient space is provided for the chains which are thus protected from 75 contact with the logs (which they might foul 80 if arranged exposed along the top or sides of the bunk) as well as from being interfered with by anything else. Moreover, as was said above, the inverting of the channel-plate provides a broad-bearing face for the 85 logs. Upon such face there may be conveniently provided, if desired, a strip *b*⁴ extending from end to end of the bunk, to prevent the logs from slipping lengthwise. 90

The fastening means *o*¹ for the end of each 95 of the chains *t* consists preferably of a simple notched piece, such as an angle plate one face of which is secured to the side of the bunk and the other face having a V-shaped or otherwise suitably formed notch in which the chain may be engaged and held by the sides of the notch by simply laying it therein. Thus, when one of the stakes is to be drawn up to its elevated position before the loading on of the logs commences, the end of corresponding chain is drawn up tightly and laid into the corresponding notch the sides of which act like jaws to hold the chain tightly against slipping. 105 When the logs are to be dumped, the chain or chains are simply lifted from their notches and thereby released.

I claim as my invention:

1. In a logging car or truck, the combination with the stakes to retain the logs, and 110

- the stake-controlling chains, of a center sill, and a bunk consisting of a hollow top member adapted to form a support for the logs and laid transversely above the center sill, 5 a bottom member extending transversely below the center sill, means to unite said top and bottom members, the said chains extending from side to side within the hollow of the top member, and means to keep the bunk 10 from twisting upon the center sill.
2. In a logging car or truck, the combination with the stakes to retain the logs, and the stake-controlling chains, of a center sill, and a bunk consisting of a straight inverted 15 channel plate laid transversely above the upper surface of the center sill, a channel plate extending transversely below and bent around the under surface of the center sill, the said chains extending from side to side 20 within the channel of the said inverted plate, and angle plates located at the junction of the bunk and center sill to prevent the bunk from twisting upon the center sill.
3. In a logging car or truck, the combination 25 with the stakes to retain the logs, and the stake-controlling chains, of a center sill, and a bunk consisting of a hollow top member adapted to form a support for the logs and laid transversely above the center sill, a 30 bottom member extending transversely below the center sill, plates at each end of the bunk to unite the top and bottom mem-

bers, the said chains extending from side to side within the hollow of the top member, means upon the plates at the ends of the 35 bunk to secure the ends of the chains, and means located at the junction of the bunk and the center sill to keep the bunk from twisting upon the center sill.

4. The combination to form a logging car, of a frame including a center sill, a pair of bunks each having a top member and a bottom member laid respectively across the top and bottom of the center sill, the top members being of substantial depth to form a 45 support for the logs substantially above the plane of the frame, means to unite the top and bottom members of the bunk on each side of the center sill, means at each end of each bunk to retain the logs, and means to 50 keep the bunks from twisting upon the center sill; thus providing upon and uniting to the frame two transverse members adapted to support logs without unduly exposing the frame to the latter and at the same time 55 firmly securing the transverse members to the frame.

This specification signed and witnessed this 27th day of April, A. D., 1911.

BASIL MAGOR.
